UNITED STATES PATENT OFFICE.

ALEXANDER E. MARDORE, OF DENVER, COLORADO.

BOTTLE-STOPPER.

No. 890,528.

Specification of Letters Patent.

Patented June 9, 1908.

Application filed September 9, 1907. Serial No. 392,041.

To all whom it may concern:

Be it known that I, ALEXANDER E. MARDORE, a citizen of the United States, residing at Denver, in the county of Denver and State of Colorado, have invented certain new and useful Improvements in Bottle-Stoppers; and I do hereby declare the following to be a full, clear, and exact description of the invention, such as will enable others skilled in the art to which it appertains to make and use the same.

This invention relates to bottle closures, and has for an object to provide a closure adapted for use as a secondary or auxiliary closure for a bottle after the original closure has been moved.

The closure is designed for use upon any ordinary form of bottle, but especially those in which effervescent and volatile substances are ordinarily contained, and affording means for readily opening the said bottle when the contents are required and as readily closed, and has for a further object to provide a closure readily operated by the hand in which the bottle is held so as not to obstruct the ready use by one hand while the other hand holds a receptacle in which the contents are to be poured.

With these and other objects in view, the invention comprises certain novel constructions, combinations and arrangements of parts, as will be hereinafter fully described and claimed.

In the drawings:—Figure 1 is a view of the improved closure in side elevation. Fig. 2 is a view of the improved closure in diametrical vertical section showing a conventional bottle neck in association therewith.

Like characters of reference designate corresponding parts throughout the several views.

The closure forming the subject-matter of this application comprises a shell or casing 10 of a size sufficient to be passed over the neck of the bottle upon which it is to be used and provided adjacent its lower end with an annular shoulder 11 against which abuts an elastic gasket 12 which is maintained in contact with the said shoulder by means of an annular screw ring 13 or in any approved manner. The screw ring 13 is provided with an opening sufficient in size to permit the insertion therethrough of a bottle neck as 14 upon which the device is used, and the annular elastic ring 12 is also provided with a central opening sufficient in size to permit

the lip or finish of the bottle neck to be forced therethrough and to firmly and hermetically embrace the neck of the bottle below the finish.

The upper end of the shell 10 is provided with an opening 15 through which the contents of the bottle is to be poured and with an arm or off-set 16 extending laterally therefrom and bent or curved as at 17 to form an inclined portion extending upwardly over the opening 15.

Within the angle formed by the arms 16 and 17 a spring or resilient member 18 is mounted in any approved manner as by being secured to the arm 16 and to the said spring member 18 an elastic closure 19 is secured in any approved manner as by a screw 20 inserted through the spring member 18 and into the closure 19.

The arm 17 is provided with a slot or opening 21 within which is pivoted a hopper 22 having a thumb button or other means for manipulating at one end, as shown at 23 and with the opposite end curved as at 24 to engage the upper side of the spring member 18 and to force the said spring member and its associate closure 19 downwardly into engagement with the casing 10 and into the upper open end thereof as shown particularly in Fig. 1 in closed position.

It will be understood that when the closure is in the position shown at Fig. 1, the upper opening 15 is closed so that the contents of the bottle is conserved, while when the thumb button 23 is forced upwardly the resiliency of the spring 18 carries the closure 19 upwardly therewith and opens the upper end of the casing 10 as shown at Fig. 2 permitting the contents to be poured therethrough.

As soon as the contents of one bottle has been removed the closure may be removed from such bottle and replaced upon another bottle from which the usual and ordinary cork or other closure has been previously removed.

What I claim is:—

1. A bottle closure comprising a shell, means carried by the shell for engaging the neck of a bottle, a stopper adapted to close the shell, means to maintain the stopper normally in open position, and means for forcing the stopper into engagement with the shell.

2. A bottle closure comprising a shell, an elastic member carried by the shell and proportioned to engage the neck of a bottle, a

- spring carried stopper arranged to remain normally out of engagement with the shell, and means to force the stopper into engagement with and to close the shell.
5. 3. A bottle closure comprising a shell, an elastic ring carried by the lower end of the shell, and proportioned to engage the neck of a bottle, a stopper, and means to maintain the said stopper in a closed relation with the shell.
10. 4. A bottle closure comprising a shell open at each end, and having an annular shoulder formed internally adjacent the lower end of the shell, an elastic ring mounted within the shell and in engagement with the shoulder, an annular ring in engagement with the lower end of the shell, and adapted to maintain the elastic ring in operative position, an arm outstanding laterally from the upper end of the shell, a spring mounted upon the arm, an elastic stopper carried by the spring and adapted to close the upper end of the shell, and a lever pivoted upon the arm and adapted to force the stopper into and maintain it in closed relation to the shell. 25
- In testimony whereof I affix my signature in presence of two witnesses.

ALEXANDER E. MARDORF.
